INVENTOR,
Isaac P. Wendell

UNITED STATES PATENT OFFICE.

ISAAC P. WENDELL, OF PHILADELPHIA, PENNSYLVANIA.

CAR-AXLE BOX.

SPECIFICATION forming part of Letters Patent No. 243,820, dated July 5, 1881.

Application filed October 1, 1880. (No model.)

To all whom it may concern:

Be it known that I, ISAAC P. WENDELL, a citizen of the United States, residing at Philadelphia, in the county of Philadelphia, in the State of Pennsylvania, have invented a new and useful Improvement in Car-Axle Boxes, of which the following is a specification, reference being had to the accompanying drawings, in which—

10 Figure 1 is a longitudinal vertical section of an axle-box embodying my improvements. Fig. 2 is a front elevation of the same, partly in section. Fig. 3 is a detail side elevation of axle-box lid and attached pumping mechanism. Fig. 4 is a vertical longitudinal section of the oil-pump. Fig. 5 is a front elevation of the same, partly in section. Fig. 6 is an elevation of a modification of my invention. Fig. 7 is a vertical transverse section of the same; 20 and Fig. 8 is a plan, partly in section, of a still further modification.

25 My invention relates to that class of car-axle boxes in which the pumping mechanism for supplying oil to the journal-bearings is operated by the jolting action of the car produced by traveling over the uneven portions of the track or from other causes, and has for its object to secure said pumping apparatus to a detachable frame or lid, for the purposes hereinafter more fully set forth.

30 My invention accordingly consists in the provision to a car-axle box of a lid or detachable frame constructed in such a manner that the oil-pumping mechanism is solely attached thereto and placed within or upon the same, whereby when the lid is removed from the axle-box the pump follows therewith, thus permitting of the application of my invention to any axle-box now in use without necessitating 35 any alterations therein or additions thereto.

40 Referring to the annexed drawings, A represents the axle-box, of the usual or any suitable construction. B is the lid thereof, and is formed with a recess or chamber, b, in which 45 is placed a pump, C. The latter is constructed substantially like that shown in my former patents for car-axle boxes, having an oil-passage, D, which terminates in an opening, e, in the journal or axle-bearing E. Said pump is 50 held in position in the chamber b by the lugs

b' b'', which depend from the upper side, b², of said lid and fit into recesses c' c'' in the upper edge of said pump, so as to leave a space or interval, c², between the said edge of the pump and the side b² of the lid B. Said pump is 55 also provided with a branch tube, C', which dips down into the oil-well A', as shown. Said pump C and oil-passage D are respectively provided with valves d' and c'', as shown; or they may be located in any other suitable position in said parts.

60 F is the plunger, having a rod, f, which is of a less diameter than that of the plunger, so that any oil that finds its way up past said plunger will not be received upon or adhere 65 to the rod f, but will pass off therefrom through the space c² and drip back to the oil-well A', thus preventing any escape of oil from the plunger-rod opening in the side b² of lid B.

To the rod f is secured a weight, G, and 70 surrounding said rod is a spiral spring, H, one end of which rests upon side b² of lid B, the other bearing against the weight G, thereby forming a spring-support for said weight and plunger-rod.

75 If desired, the upper end of the stem f may have a bearing in the standard I, projecting from or formed integral with the lid B.

The operation is obvious. As the car to which said boxes are applied travels along, the 80 jolting of the same causes the weight G and plunger-rod to rise and fall on its spring-bearing H, thereby reciprocating the plunger F to raise and force oil from the well A' to the journal or axle-bearing E, the oil so pumped 85 passing through oil-passage D, and is distributed by the ducts e' e'' to all parts of bearing E, the surplus oil falling from the latter into the well A'. The pump and its appendages being secured to lid B, no specially-formed 90 axle-box is required, and said parts are readily removed for repairs, &c., and then as easily replaced in position.

95 Figs. 5 and 6 show a modification of my invention, wherein the weight G is placed below the pump C and held suspended upon rods g, which are secured to a cross-bar, g', affixed to the plunger-rod f. The spring H encircles said rod, as shown. The lid B being formed with three recesses or chambers, b⁴ b⁵ b⁶, in 100

which are respectively placed the spring H, pump C, and weight G, so that said parts are covered and protected from dust or injury.

K is a ledge formed on lid B to conduct the drip from pump C back to the well A'.

Fig. 7 shows another modification, wherein I employ a frame, L, fitting loosely in guides *ll* in the box A, and having a cover, M. In said frame is placed the pump, which is secured thereto. The axle-box lid N is then made plain or in the usual manner. The latter construction I prefer to use when new boxes are to be built; but when my invention is to be applied to axle-boxes already constructed or in use, I prefer to attach the pump to box-lids formed with a recess or recesses, as first above described.

What I claim as my invention is—

1. The axle-box lid B, having a chamber, *b*, and depending lugs *b' b'*, in combination with pump C, secured to said lid and held by said lugs, substantially as shown and described.

2. In a car-axle box, a detachable lid or frame to which is secured and held supported thereby an oil-pumping device, a weight and spring attachments, arranged substantially as shown and described, whereby when said lid or frame is removed from the axle-box, the pumping mechanism and attachments follow therewith.

In testimony that I claim the foregoing, I have hereunto set my hand this 15th day of July, 1880.

ISAAC P. WENDELL.

Witnesses:

B. F. TELLER,
ALBERT LUPTON.
